Des. 193,389
Patented Aug. 14, 1962

193,389

PLATFORM UNIT FOR THE REAR SEAT OF A CAR

Gerald E. Kardach, 2114 W. Juneau Ave.,
Milwaukee, Wis.

Filed Aug. 12, 1959, Ser. No. 57,162

Term of patent 14 years

(Cl. D14—6)

FIG. 1 is a top perspective view of a platform unit for the rear seat of a car, embodying my new design.

FIG. 2 is a bottom perspective view.

I claim:

The ornamental design for a platform unit for the rear seat of a car, as shown.
